(57) **CLAIM**

The ornamental design for a light fixture lens and bezel, as shown and described.

DESCRIPTION

FIG. 1 is a perspective view of a light fixture lens and bezel embodying my design;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken line showing is included for the purpose of illustration only and forms no part of the claimed design.
